UNITED STATES PATENT OFFICE.

HENRY SUYDAM CROOKE AND LEWIS CROOKE, OF NEW YORK, N. Y.

MANUFACTURE OF ORNAMENTAL METALLIC FOIL.

SPECIFICATION forming part of Letters Patent No. 295,986, dated April 1, 1884.

Application filed July 15, 1880. (No model.)

To all whom it may concern:

Be it known that we, HENRY SUYDAM CROOKE and LEWIS CROOKE, both of the city, county, and State of New York, have made 5 an invention or discovery of an Improvement in the Manufacture of Ornamental Metallic Foil; and we do hereby declare the following to be a full, clear, and exact description of the same.

- 10 The object of our invention is to produce the article of manufacture consisting of tin-foil having burnished letters, words, marks, figures, or designs on a dead or white ground, or the reverse, and thus rendered visible and 15 distinct by reason of the contrast with the ground; and our invention consists in the method of and in machinery for producing the same, as will be hereinafter fully described and claimed.
- 20 In order that our invention may be fully understood, we have represented in the accompanying drawings an apparatus for carrying out our invention.

Figure 1 of said drawings represents a side 25 view of said apparatus. Fig. 2 represents a section of the apparatus through the line *a a* of Fig. 1.

The apparatus represented in said drawings consists, mainly, of rollers for operating upon 30 the foil, of a reel from which the foil is unrolled to be passed to the rollers, and of a second reel upon which the foil is wound after being operated upon by the rollers.

The roller A is of steel or other suitable 35 metal, which is first turned true, and preferably polished, and then has all of its surface, except those portions corresponding with the parts of the tin-foil which are to be left bright or burnished, striated, grained, matted, or stippled. In the drawings this main roller 40 is represented as being grained, with the exception of a five-pointed star, which is left smooth. This roller is supported in suitable stands, B B, having suitable boxes, C, for its 45 shaft or journals D. Immediately above this roller is a counter-roller, E, made preferably with a shaft, f, sustained in boxes which can be pressed toward the roller A by means of powerful screws G, the said shaft f being sur- 50 rounded with a body of paper or other slightly yielding material. The counter-roller may, however, be of metal, and grained, striated,

matted, or stippled, the counterpart of that produced on the metal roller first described; or said counter-roller may be of metal with a 55 smooth surface.

We prefer that where the counter-roller is made of a shaft surrounded by a body of paper or other slightly-yielding material it be kept moist by a liquid, as described in Letters Patent of the United States granted to us July 6, 1880, No. 229,677. Where the counter-roller is of metal and smooth, or where it is grained, striated, matted, or stippled to correspond with the other roller, it is necessary to gear the two rollers together, so that they shall run with the same superficial speed and articulate. Where the dry slightly-yielding counter-roller is employed, it is preferable 60 that it should be geared to run at the same 65 superficial speed as the other roller. Where liquid is employed with the yielding roller, it need not be geared, unless desired, with the other roller.

In practicing our invention we pass the bur- 75 nished tin-foil between the main and counter rollers, unwinding on one reel and winding up on the other, the tin-foil issuing from between these rollers, acted upon by the striated, grained, matted, or stippled surface of the 80 main roller, having a dead or white surface, while those portions of the tin-foil that correspond with the portions of the surface of the main roller that have not been striated, grained, matted, or stippled will be left bright or bur- 85 nished.

Any letters, words, marks, figures, or designs desired can be produced on the main roller by stippling, striating, graining, or matting all its surface except such portions as correspond with the letters, words, marks, figures, or designs that are to be left bright or bur- 90 nished on the tin-foil.

It is obvious that the tin-foil can be produced with the words, letters, marks, figures, 95 or designs having a dead or white surface on a bright or burnished ground, the reverse of that just described, by striating, graining, matting, or stippling the portions of the surface of the main roller that correspond with the portions to be left dead or white upon a burnished ground, the rest of the roller being left smooth.

We do not herein claim the article of manu-

facture of ornamental metallic foil having letters, words, marks, figures, or designs upon a roughened, dead, or white ground, or the reverse, and thus rendered visible and distinct by reason of the contrast with the ground, as that forms the subject-matter of the United States Patent granted to Henry Suydam Crooke, dated August 29, 1882, No. 263,321.

What we claim, however, as new, and desire to secure by Letters Patent, is—

1. The method of ornamenting metallic foil by passing it between two rollers, one of which has all of its surface, except what corresponds with or is the counterpart of that to be produced burnished or bright on the surface of the foil, or the reverse, striated, grained, matted, or stippled, while those portions the counterpart of that to be produced burnished or bright on the surface of the foil are smooth,

and the other of which is a counter-roller to 20 press the foil in contact therewith, substantially as described.

2. The combination of a main roller having its surface the counterpart of that to appear burnished or bright on the tin-foil smooth, 25 while that portion that is to appear dead or white on the tin-foil is grained, striated, matted, or stippled, with a counter-roller, substantially as described.

In testimony whereof we have hereunto set 30 our hands in the presence of two subscribing witnesses.

HENRY SUYDAM CROOKE.
LEWIS CROOKE.
